UNITED STATES PATENT OFFICE.

WILLIAM A. RIDDELL, OF ROCHESTER, NEW YORK, ASSIGNOR TO EASTMAN KODAK COMPANY, OF ROCHESTER, NEW YORK, A CORPORATION OF NEW YORK.

WINDING-KEY FOR PHOTOGRAPHIC-FILM CAMERAS.

1,266,319.

Specification of Letters Patent. Patented May 14, 1918.

Application filed November 30, 1915. Serial No. 64,357.

To all whom it may concern:

Be it known that I, WILLIAM A. RIDDELL, of Rochester, in the county of Monroe and State of New York, have invented certain new and useful Improvements in Winding-Keys for Photographic-Film Cameras; and I do hereby declare the following to be a full, clear, and exact description of the same, reference being had to the accompanying drawings, forming a part of this specification, and to the reference-numerals marked thereon.

My present invention relates to photography and more particularly to photographic cameras or roll holders and it has for its object to provide a simple, cheap and efficient winding key for the take-up spool of a film roll. A further object of the invention is to provide a winding key mechanism that may be easily and rapidly assembled together and readily attached to the camera body or roll holder casing and the improvements are directed in part toward the means for holding the winding key in operative and inoperative positions as it is pushed into engagement with the spool or withdrawn therefrom. To these and other ends the invention resides in certain improvements and combinations of parts all as will be hereinafter more fully described, the novel features being pointed out in the claims at the end of the specification.

In the drawings:

Fig. 1 is an elevation of a fragment of a camera wall provided with a film winding key constructed in accordance with and illustrating one embodiment of my invention;

Fig. 2 is a section on the line 2—2 of Fig. 1 with the key in operative or winding position;

Fig. 3 is a similar view with the key retracted to inoperative position;

Fig. 4 is a transverse section taken substantially on the line 4—4 of Fig. 3;

Fig. 5 is a similar section taken on the line 5—5 of Fig. 2;

Fig. 6 is a section taken substantially on the line 6—6 of Fig. 2 in the plane of the under face of the cap;

Fig. 7 is a plan view of the socket shell and clutch block with the cover plate removed and taken in section through the spindle, and

Fig. 8 is a collective perspective view of the

parts forming the head of the spindle arranged in the order in which they are assembled.

Similar reference numerals throughout the several views indicate the same parts.

The general mode of operation of the film winding key is a matter of common knowledge and it is thought not to require detailed description here beyond reference to the fact that the spool engaging portion of the key is thrust into a film spool chamber to coöperate with a recess in the end of the spool and lock it in place and turn it and is withdrawn flush with the inner surface of the chamber to disengage the spool and permit its withdrawal. In the present instance, the camera wall inclosing the film chamber is indicated at 1 and has an aperture 2 extending therethrough and an adjacent recess within which fits a cup-shaped or cylindrical socket shell 4 having laterally turned flanges 5 disposed against the outer face of the camera to secure it in place. At opposite sides the shell is provided with inwardly extending projections 6 which lock into corresponding recesses 7 in the periphery of a cylindrical clutch block 8 and prevent it from turning. The shank of a spindle 9 extends centrally through the clutch block 8 and shell 4 and recesses 10 at the center of the clutch block contain ball or roller clutches 11 of a familiar type which are urged toward the narrow ends of the recesses by springs 12 to allow the spindle to be turned in one direction only.

The clutches just described do not, however, prevent longitudinal or axial movement on the part of the spindle at the inner end of which is a blade or cross piece 13 forming a spool engaging head. This head may be projected beyond the wall 1, as shown in Fig. 2, to coöperate with the spool or retracted into the aperture 2, as shown in Fig. 3, by sliding the spindle longitudinally. This longitudinal movement is resisted by a contracting spring ring 14 to prevent a loose movement of the spindle and in the present instance, this ring is carried in an annular chamber 15 beneath a cover plate 16 and between the latter and the clutch block 8. The cover plate holds the ring in fixed position and also confines the clutch block and is secured to the camera wall by screws 17 passing through it and also through the flanges 5 of the socket shell 4. When the

spindle is in the operative position of Figs. 2 and 5, the ring 14 co-operates with a peripheral notch or groove 18 on the spindle and yieldingly locks the latter in that position from which it may be withdrawn by an outward pull to ride on the peripheral surface and still offer a frictional resistance. The outer end of the spindle is preferably enlarged as at 19 and referring more particularly to Fig. 8, this enlarged portion or head is provided on its outer face with a transverse or diametrically extending channel 20 and also with a shallower central recess 21. The ends of the channel form journal bearings for trunnions 22 on the ends of a yoke shaped handle or finger piece 23 that spans the enlarged end of the spindle as shown in Figs. 1 and 6. A spring plate or washer 24 occupies the recess 21 and is provided with lateral ears 25 that resiliently engage the trunnions 22. These latter are squared or have flat faces, as clearly shown in Fig. 8 and the yielding pressure of the ears 25 thereon maintains the handle 23 in either the folded inoperative position of Figs. 1, 2, and 6 or the outstanding operative position of Fig. 3 and by means of the handle the spindle may be turned or pushed in or pulled out.

I prefer to provide a cap 26 to fit over the enlargement 19 of the spindle and inclose the parts associated therewith. This cap is also spanned by the handle and has openings 27 to admit the trunnions 22. It is held in place at its center by a screw 28 passing axially into the spindle and also holding in place the plate 24.

It will be observed that a winding key constructed in accordance with my invention is composed of few and simple parts and is very readily assembled as one set of parts are merely dropped into the shell 4 and secured beneath the cover plate 16 by the single set of screws 17 while the other group of parts are similarly assembled, one after another, at the end of the spindle and then secured beneath the cap 26 by the single screw 28.

I claim as my invention:

1. In a film winding key for cameras, the combination with a socket and a winding stem extending therethrough and provided with handle attaching journals opening toward the outer end thereof, of a yoke-shaped handle spanning the said outer end of the spindle and having flattened trunnions co-operating with the journals and a resilient confining plate disposed against the end of the spindle and engaging the flattened trunnions to hold the handle in a definite position.
2. In a film winding key for cameras, the combination with a socket and a winding stem extending therethrough and provided with a cavity in its outer end face and with a diametrically extending channel forming handle attaching journals, of a yoke-shaped handle spanning the said outer end of the spindle and having flattened trunnions co-operating with the journals, and a confining plate occupying the cavity in the spindle end and provided with ears engaging the flattened trunnions to hold the handle in a definite position.
3. In a film winding key for cameras, the combination with a socket and a winding stem extending therethrough and provided with a cavity in its outer end face and with a diametrically extending channel forming handle attaching journals, of a yoke-shaped handle spanning the said outer end of the spindle and having flattened trunnions co-operating with the journals, a confining plate occupying the cavity in the spindle end and provided with ears engaging the flattened trunnions to hold the handle in a definite position, a cap also spanned by the handle and having openings to admit the trunnions and a single fastener extending axially into the spindle to secure the cap, plate and handle thereto.

WILLIAM A. RIDDELL.
